EXHAUST AND SUCTION NOZZLE

Fred H. Carroll, Jacksonville, Fla.

Application September 15, 1941, Serial No. 410,908

4 Claims. (Cl. 230—100).

This invention relates to improvements in exhaust and suction nozzles for locomotive engines, stationary engines and internal combustion engines.

It is the primary object of this invention to provide an improved, simple and highly efficient exhaust and suction nozzle which is of simple and sturdy construction, can readily and easily be assembled and effects substantial reduction of back-pressure in an engine.

Another object of the invention is the provision of an exhaust and suction nozzle of the type referred to above which embodies an axial exhaust passage, and a plurality of suction passages arranged in the circumferential wall of the nozzle for direct communication of said suction passages with the exhaust passage, and provided with inclined side walls to effect axially offset intersection of the exhaust stream with the suction streams and encircling of the exhaust stream by the suction streams when drawn into the exhaust passage.

Still another object of the invention is the provision of an exhaust and suction nozzle of the type referred to above which embodies an axial exhaust passage and a plurality of elongated, upwardly inclined suction passages arranged in the circumferential wall of the nozzle and provided with inclined side walls to effect axially offset intersection of the exhaust stream with the suction streams and encircling of the exhaust stream by the suction streams for rotation of the suction streams in screw lines around the exhaust stream when drawn into the exhaust passage by the exhaust stream and discharged therefrom together with the exhaust stream.

With these and incidental objects in view, the invention consists in certain novel features of construction and combination of parts, the essential elements of which are set forth in the appended claims; and a preferred form of embodiment of the invention is hereinafter shown with reference to the drawing accompanying and forming part of this specification.

In the drawing:

Fig. 1 is a side-view of an exhaust and suction nozzle according to the invention.

Fig. 2 is a vertical sectional view through the exhaust and suction nozzle shown in Fig. 1, the section being taken on line 2—2 of Fig. 3; and

Fig. 3 is a cross-sectional view through the exhaust and suction nozzle, the section being taken on line 3—3 of Fig. 1.

Referring now in detail to the exemplified form of the invention shown in the drawing,

reference numeral 2 denotes my improved exhaust and suction nozzle which embodies a passaged, cone-shaped body 3, and a ring-shaped top member 4 seated upon body 3 and secured thereto by means of bolts 5. Body 3, at its upper portion 6, is provided with a plurality of downwardly extended, symmetrically arranged posts 7 which are integrally formed with body 3, have elongated cross section and are provided with threaded bores 8 for bolts 5. The posts 7 support and mount ring-shaped top member 4 which is larger in diameter than body 3 and has downwardly extended therefrom a plurality of posts 9 with bores 10 for bolts 5. Posts 7 and 9 have the same cross section, are equal in number and arranged in alignment with each other to permit the bolts 5 being readily extended through bores 10 in top member 4 and threaded into bores 8 for attachment of top member 4 to body member 3.

Posts 7 and 9, the cross sections of which are elongated, are arranged so that the suction streams drawn through passages 11, formed by these posts and body and top members 3 and 4, non-axially intersect the exhaust stream discharged through central passage 12 in body 3 (see Fig. 3) and advance in rotary movements around the exhaust stream. The discharged exhaust stream embodies a central exhaust stream and a plurality of suction streams traveling in screw lines around the central exhaust stream, an arrangement which reduces formation of turbulent streams in the exhaust and suction nozzle and accelerates expansion of the discharged exhaust stream, thus effecting highest efficiency in the discharge of the exhaust stream into and through a smoke stack.

The top member 4, as shown, is provided with inclined wall portions 14 arranged at its bottom face between the downwardly extended posts 9, and, body member 3 has its outer wall portions 15 at the top of said body inwardly inclined, so that suction passages 11 are upwardly inclined and converge toward each other somewhat above the outlet of said nozzle.

The thus described exhaust nozzle, when attached to the exhaust of a locomotive engine, guides exhaust steam through its cone-shaped exhaust passage 12, effects acceleration of such steam in said passage, due to the decrease in cross section of passage 12, and, finally, effects discharge of such steam through the outlet 16 in top member 4. The steam passing through the nozzle effects a substantial suction at the outlets 17 of suction passages 11 and draws smoke

and combustion gas from the smoke box of the locomotive engine, it being understood, that the exhaust nozzle is mounted, as customary, in the smoke box of the locomotive engine. The suction in passages 11 of the nozzle is due to the increase in velocity of the exhaust steam near outlets 17 of the suction passages 11 and due to the inclination of the passages 11 which acts to increase the relative pressure at the inlets of passages 11. Smoke and combustion gas streams entering from passages 11 into passage 12 intersect the vapor stream flowing through passage 12 in axially offset relation, and therefore travel around such vapor stream in screw-lined streams of smoke and combustion gas (see arrows 18 in Fig. 3). Such a rotary movement of the smoke and combustion streams around the vapor stream accelerates expansion of the discharged exhaust stream and effects complete and proper filling of the smoke stack of the engine by the exhaust stream.

Having thus described my invention, what I claim is:

1. An exhaust and suction nozzle comprising a body member having an axial passage, a ring-shaped top member secured to said body member in spaced relation with respect thereto, and a plurality of spacer means extended downwardly from said top member and forming passages between said top and body members, the axes of the latter passages being inclined both circumferentially and longitudinally with respect to the axis of said axial passage to effect encircling of an exhaust stream discharged from said axial passage by streams discharged from said passages between said top and body members.
2. In an exhaust and suction nozzle a central passage, and a plurality of passages encircling

said central passage and in direct communication therewith, the axes of said plurality of passages being inclined both circumferentially and longitudinally with respect to the axis of said central passage to effect encircling of an exhaust stream discharged from said central passage by streams discharged from said plurality of passages, said latter streams rotating around said exhaust stream.

3. In an exhaust and suction nozzle a central main passage, and a plurality of upwardly inclined auxiliary passages arranged circumferentially around said central passage and in direct communication therewith, the axis of said auxiliary passages being inclined both circumferentially and longitudinally with respect to the axis of said central main passage to effect rotary encircling of an exhaust stream discharged from said central main passage by secondary streams discharged from said auxiliary passages.
4. An exhaust and suction nozzle comprising a body member having an axial passage, a plurality of ribs with elongated cross sections integrally formed on the outside wall of said body member, a ring-shaped top member with downwardly extended spacer means having cross sections similar to those of said ribs, said spacer members being upon the ribs of said body member, and means rigidly connecting said top member in adjusted position to said body member, said ribs and spacer means being arranged so that the longer axis of the cross sections of adjoining ribs and spacer means intersect each other in points axially offset with respect to the axis of said axial passage to effect encircling of a stream discharged from said axial passage by streams rotating around such first stream.
